Term of patent 3½ years

(Cl. D14—30)

To all whom it may concern:

Be it known that I, Robert Schilling, have invented a new, original, and ornamental Design for a Wheel or Similar Article, of which the following is a specification, reference being had to the accompanying drawing, forming a part hereof.

Fig. 1 is a perspective view of a wheel incorporating my new design; and

Fig. 2 is a sectional view taken substantially through the mid-plane of Fig. 1.

The dominant feature of my design resides in the full line portion of the drawing.

I claim:

The ornamental design for a wheel, substantially as shown and described.
